UNITED STATES PATENT OFFICE

CHARLES EISLER, OF NEWARK, NEW JERSEY, ASSIGNOR TO EISLER ELECTRIC CORPORATION, OF NEWARK, NEW JERSEY

DISK VALVE FOR BURNERS

Application filed June 17, 1930. Serial No. 461,673.

The invention relates to a burner such as used for heating glass tubes for neon signs and for other purposes when the use of the burner is intermittent.

5 The object of the invention is to provide a fixture or attachment that can be interposed between the air and gas tubes that supply the burner and the burner itself and carries a pilot light. The device is operated by a 10 handle or a treadle and alternately lights the main burner or the pilot light according to the direction in which the valve is turned.

The valve is of simple construction and is 15 readily attached and detached to and from the burner structure.

The invention is illustrated in the accompanying drawings in which Figure 1 is a front view of a burner and showing the improved regulator or valve for use therewith. 20 Figure 2 is an end view of the upper part of Figure 1.

The main burner of my desired construction and the one illustrated is supported on a base 10 with the supporting pipe 11 which 25 acts as a mixing chamber for the burner 12. The gas is supplied through the pipe 13 usually provided with a valve 14 and the air is supplied through pipe 15 provided with a valve 16. In ordinary burners the flexible 30 hose 17 for the gas and the flexible hose 18 for the air are attached directly to the burner pipes 13 and 15.

I interpose between the hose and the valves, a regulator which has two outlets, one, 19, 35 connected to the gas pipe 13 by the union 20 and the other, at 21, connected by the union 22 to the air pipe 15. The outlets are arranged in the member 23 which with the other member 24 constitutes the main body of the 40 regulator. The two members are flat and have ground faces which abut to form a tight joint. The member 24 has two inlets one of which is supplied with a pipe 25 to receive the 45 hose 17 and the other has a pipe 26 which receives the hose 18.

The inlets and outlets in the valve members extend through their respective members and when in line supply fuel and air to the pipes 13 and 15 and thus to the main 50 burner. When placed out of register they

cut off the supply to the main burner. The two members are rotatable one relative to the other. They are mounted on a shaft 27 which is provided with a spring 28 which bears on the shoulder 29 on the shaft 27 and 55 as the cotter pin 30 or its equivalent rests on the member 24. The member 24 is kept constantly pressed against the member 23. The two members are arranged normally out of register as to the inlet and outlet openings. 60 The spring 31 is connected to an arm 32 on the rotatable member 24 and to an arm 33 on the fixed member 23. The stud 34 on the arm 33 is engaged by a pin 35 on the member 24 to limit the rotative movement of the 65 member 24 in one direction and by a jam 36 on the same member to limit the movement in the other direction.

The rotatable member 24 is actuated by any suitable mechanism and I show a rod 70 37 which can be secured to a foot treadle for turning the burner on and when released allowing the spring 31 to turn the supply to the main burner off.

One of the members, such as 23, has a 75 groove or duct 38 which is connected to the inlet 25 when the main burner is shut off. This groove connects with a small pipe 39 which leads to the top of the main burner and has its end directed to the burner surface and furnishes a pilot light at the end 40. The pipe 39 may have a cock 41 for controlling the amount of flame at the pilot light. 80

The operation is evident and when the main burner is shut off by releasing the 85 treadle and the spring 31 holds the inlet and outlet ports of the valve out of register, the movable valve member directs gas into the pilot light tube or pipe 39. When the treadle is pressed the main gas and air pipes of 90 the burner are supplied with fuel and the main burner is available for use.

I claim:—

1. An attachment for burners comprising 95 a pair of valve elements of disk like form, one mounted so as to partially rotate relative to the other, the members having inlets in one and outlets in the other and adapted to be placed in register when the one is partially rotated and a passage in one valve 100

member for feeding a pilot light, said passage being disposed to be in communication with one inlet of the rotatable member when said member is in normal position.

- 5 2. A valve comprising two flat members mounted to permit one to rotate on the other, inlets and outlets in the members to be placed in register when the one member is partially rotated, stops to limit the rotatable movement in both directions, means for yieldingly holding the rotatable member in normal position, and a groove in the fixed member and positioned to receive fluid from one inlet of the rotatable member when it is in normal position and cut off the outlet of the fixed member.

In testimony whereof he affixes his signature.

CHARLES EISLER.
